UNITED STATES PATENT OFFICE.

RALPH E. H. POMEROY, OF MCGILL, NEVADA.

ROASTER-FURNACE TOP.

1,251,692.

Specification of Letters Patent. Patented Jan. 1, 1918.

Application filed April 4, 1917. Serial No. 159,619.

To all whom it may concern:

Be it known that I, RALPH E. H. POMEROY, a citizen of the United States, residing at McGill, in the county of White Pine and State of Nevada, have invented a certain new and useful Improvement in Roaster-Furnace Tops, of which improvement the following is a specification.

This invention relates to devices for preparing ore and concentrates for roasting in metallurgical furnaces, and more particularly for the multiple hearth type of furnace having a series of superimposed working chambers and operated by a revolving center shaft or column with projecting rabble arms in the various chambers.

Where ores are prepared by what is known as the flotation process, the resulting concentrate, which often contains a large amount of alumina, is of a very sticky consistency, and very difficult to handle, and the objects of my invention are to provide an improved drying hearth for treating this material, and heated solely by the waste heat of the furnace; to provide improved means for thoroughly mixing and stirring said material, and for feeding the same from the drying hearth into the uppermost chamber of the furnace; to provide a drying hearth freely open to the atmosphere and having a gas sealing means between said drying hearth and the upper chamber of the furnace; and to otherwise simplify and improve apparatus for preparing such ores and concentrates for roasting.

In the accompanying drawings: Figure 1 is a vertical section of a roaster furnace top embodying my improvement; Fig. 2, a half plan of same; Fig. 3, a horizontal section; and Fig. 4, a vertical section of a portion of the gas seal and means for feeding ore into the upper chamber of the furnace.

While my improvement may be employed in connection with various types of metallurgical furnaces, I have illustrated the same as applied to multiple hearth roaster furnaces having a series of superimposed working chambers, operated by a revolving vertical center shaft or column, 3, having projecting rabble arms, 4, in said chambers. The drawing shows the uppermost working chamber, 5, of the furnace, and the upper portion of the center shaft rigidly secured to the rotatable section of the stack or outlet pipe, 6, for the furnace gases, which communicates with the stationary portion,

6^a, of said pipe leading out through the wall or roof of the building to the flue or atmosphere. The stationary portion of said pipe may be supported on the furnace frame work, 7, and the upper end of the rotatable section, 6, may be guided by means of a plurality of rollers or wheels, 8, mounted on trunnions, 9, carried by the frame and engaging a metal ring, 10, mounted on the upper end of the rotatable section, 6.

According to my improvement, a drying hearth is located directly on the top of the uppermost working chamber of the furnace, the roof of said chamber also constituting the floor, 11, of said hearth whereby the waste heat from the furnace may be transmitted through said floor and be thus utilized for heating and drying the ore and concentrates prepared on said drier hearth. 75 The floor of the drier hearth which is located around the revoluble center column or pipe, is preferably composed of a series of segmental metal plates, 11^a, and another set of circumferential plates, 11^b, supported on 80 brackets, 11^c, attached to the inner shell of the furnace wall, said floor also forming the roof of the uppermost working chamber of the furnace. The drier hearth is provided with an outer cylindrical side wall, 12, and 85 is freely open at the top to the atmosphere for the ready escape of vapors of evaporation of the ore or concentrate.

For the purpose of thoroughly mixing and stirring the ore or concentrate during the 90 drying process, various forms of mechanism may be employed, operated by the revolving center column, and I have shown a preferred construction comprising a plurality of radial arms, 13, rigidly secured at their inner ends 95 to the column or pipe, 6, and each suitably connected to a horizontal rotatable shaft, 14, carrying a series of disks, 15. These horizontal shafts are set at an acute angle to the respective arms, and are shown as connected therewith by any suitable means such as a universal bearing, 16, at the inner end and a chain, 17, at or toward the outer end. The length of the chains may be readily adjusted by suitable hooks to give the desired angle 105 of inclination of the disk shafts to the radial arms.

As a preferred construction, there are shown four disk shafts, 14, on which are mounted, at suitable intervals, circular concave plates or disks, 15, the disks on two alternate shafts being so dished as to turn

the material from the outer side toward the center of the hearth, and the disks on the two opposite shafts being so dished as to turn the material from the center toward the outside of the hearth. The disks, 15^a, located at or toward the outer ends of shafts, 14, are of greater diameter than the other disks, so as to support the outer ends of the shafts and engage the outer circumferential set of floor plates, 11^b, whereby all of the wear of the disks upon the floor is taken by this outer set of floor plates, which may be made of hard cast iron or other metal and may be readily renewed when they become worn. These larger disks are the only ones in contact with the floor and govern the speed of revolution of the shafts, 14.

One or more of the shafts may be provided with a small trailer disk, 15^b, connected by an arm, 15^c, to the end of the shaft, 14, for the purpose of trimming the edges of the material upon the hearth, and bringing it within range of the larger disk rigidly mounted on said shaft.

The gases from the working chambers of the furnace escape through the central flue, 6 and 6^a, which may lead through the roof or side wall of the building, and are prevented from escaping through the drier hearth by gas sealing means which may comprise a cylindrical plate, 18, rigidly secured by a circular plate or casting, 19, to the revolving column or pipe, 6, and a horizontal annular feeder plate, 20, supported at the inner edge of the floor by means of an angle section or casting, 21, and extending beneath the lower edge of the cylindrical plate, 18. This forms a circular trough at the inner edge of the floor and in order to feed the material from this portion of the hearth into the upper furnace chamber, the cylinder, 18, is provided with a number of small openings or slots, 22, preferably located at regular intervals around its circumference, and a corresponding number of scrapers or plows, 23, are arranged to travel around in said trough, said scrapers being preferably supported on the radial arms, 13. The gas sealing means also prevents entrance to the upper furnace chamber of vapors of evaporation given off at the top of the drying hearth.

In operation, the ore or concentrate is introduced in quantities upon the outer peripheral portion of the drier hearth, both the finer flotation concentrate and the much coarser concentrate together, and the revolving disks then stir and cut the sticky material and coat over the surfaces with particles of the coarser concentrate to prevent excessive agglomeration, the whole mass being mixed and turned by the disks backward and forward, with the result that the material is completely mixed and coated and moved across the hearth to the inner edge where the

scrapers operate to feed the same through the slots in the seal plate into the upper chamber of the furnace. During the stirring and mixing process, the sticky ore or concentrate is dried by the waste heat of the furnace acting upon the floor of the hearth, and the material is thoroughly prepared for the roasting action of the furnace.

As the material is then fed from the central portion of the drying hearth into the upper or first working chamber of the furnace, it falls through a continuous and uniform current of hot gases passing out at the central exhaust flue, thus producing the most efficient contact of the moist ore with the hot waste gases.

Having now described my invention, what I claim as new and desire to secure by Letters Patent is:

1. The combination with a metallurgical furnace having a series of working chambers with a central discharge gas flue, of a drying hearth having a floor constituting also the roof of the uppermost working chamber around the gas flue, mechanism for mixing and stirring the ore or concentrate upon said drying hearth, and means for feeding the same from the central portion of the drying hearth around the gas flue into the upper chamber of the furnace.

2. The combination with a metallurgical furnace having a series of superimposed working chambers, a vertical rotatable shaft or column, and a central discharge gas flue of a drying hearth having a floor constituting also the roof of the uppermost working chamber around said gas flue, mechanism operated by the rotatable shaft for mixing and stirring the ore or concentrate upon said drying hearth, and means for feeding the same from the central portion of drying hearth into the upper chamber of the furnace.

3. The combination with a metallurgical furnace having a series of superimposed working chambers, a vertical rotatable shaft or column, and a central discharge gas flue of a drying hearth having a floor constituting also the roof of the uppermost working chamber around the gas flue, mechanism operated by the rotatable shaft for mixing the ore or concentrate and moving it from the peripheral to the inner or central portion of said drying hearth, sealing means for preventing the passage of gases or vapor between the upper furnace chamber and the top of the drying hearth, and means for feeding the ore or concentrate from the central portion of said hearth into the upper chamber of the furnace.

4. The combination with a metallurgical furnace having a series of superimposed working chambers and a central discharge gas flue, of a drying hearth open to the atmosphere and located on the top of the fur-

nace around the flue, mechanism for mixing and stirring the ore or concentrate upon the floor of the hearth, sealing means for preventing the escape of gas to the drying 5 hearth, and means for feeding the ore or concentrate from the central portion of the hearth around the gas flue into the upper chamber of the furnace.

5. The combination with a metallurgical 10 furnace, of a drying hearth located thereon, a rotatable shaft or column at the center of the hearth, one or more radial arms operated by said shaft, horizontal rotary shafts 15 pivotally connected at one end to said arms, and disks mounted on said horizontal shafts.

6. The combination with a metallurgical 20 furnace, of a drying hearth located thereon, a rotatable shaft or column at the center of said hearth, one or more radial arms operated by said shaft, horizontal rotary shafts, each set at an angle to a radial arm, means 25 for adjusting the angle of said shaft, and disks mounted on said horizontal shafts.

7. The combination with a metallurgical 30 furnace, of a drying hearth located thereon, a rotatable shaft or column at the center of said hearth, one or more radial arms operated by said shaft, horizontal rotary shafts 35 suitably connected to said arms, and disks

mounted on said horizontal shafts, one of 30 said disks being of a larger diameter than the others and engaging the floor of the hearth.

8. The combination with a metallurgical 35 furnace, of a drying hearth located thereon, a rotatable shaft or column at the center of said hearth, one or more radial arms operated by said shafts, horizontal rotary shafts 40 suitably connected to said arms, disks fixed upon said horizontal shafts, and a trailer disk loosely mounted at the outer end of one or more of said shafts.

9. The combination with a metallurgical 45 furnace, of a drying hearth located thereon and having a circumferential series of removable floor plates, a rotatable shaft or column at the center of said hearth, one or more radial arms operated by said central shaft, horizontal rotary shafts suitably connected to said arms, and disks mounted 50 on said horizontal shafts, one of said disks being of a larger diameter than the others and engaging said series of removable floor plates.

In testimony whereof I have hereunto set 55 my hand.

RALPH E. H. POMEROY.
